UNITED STATES PATENT OFFICE.

KENNETH C. O'BRYAN AND JAMES W. O'BRYAN, OF WASHINGTON, DISTRICT OF COLUMBIA.

MEANS FOR GRADUATING CHARACTER SPACING IN A TYPEWRITER.

Application filed April 15, 1926. Serial No. 102,209.

This invention relates to improvements in typewriter constructions and particularly to a mechanism adapted for attachment to standard typewriter constructions for graduating character spacing thereof.

This invention relates to substantial improvements over the structure in Patent No. 1,457,853, granted June 5, 1923, and the constructions shown in our co-pending application, Serial No. 624,485, of October 14th, 1926.

This invention embodies substantial improvements over these previous constructions by using a principle of operation different from either of these prior structures as a result of which the construction and operation of the device has been considerably improved and simplified.

The present embodiment comprehends the provision of a pivoted or rotary member interposed between the escapement mechanism and the carriage for transmitting motion from one to the other controlled in such a way as to vary the ratio of movement between the standard movement of the escapement mechanism and the carriage so as to produce the desired or predetermined character spacing selected.

More specifically, this invention comprehends the simplification in the construction of a space graduating mechanism in which the rack bar of the standard typewriter is mounted on the carriage for relative movement thereto, with a lever pivotally connected to the carriage and the rack bar movable in the operation of the carriage and the escapement mechanism to move the carriage relative to the rack bar for varying type spacing from the standard spacing set by the escapement mechanism, which is controllable by suitable mechanism mounted on the frame of the typewriter and manually operable to obtain a desired spacing of the character in a line of typing.

The invention further comprehends numerous objects residing in the improved construction and association of parts utilizing a rotary mechanism for varying the ratio of movement between the carriage and escapement mechanism which are more particularly pointed out in the following description and in the claims directed to a preferred form of construction, it being understood, however, that various changes in the size, shape and relation of the parts may be made with-

out departing from the spirit and scope of the invention as herein set forth.

In the drawings forming part of this application:

Figure 1 is a side elevation of a typewriter shown in dotted lines with the invention applied thereto and shown in full lines,

Fig. 2 is a rear elevation of the typewriter and illustrated in Fig. 1, showing the invention applied thereto in rear elevation and in full lines,

Fig. 3 is a plan view showing the invention applied to a typewriter similar to Figs. 1 and 2,

Fig. 4 is an enlarged detail plan view of the control member and the mounting therefor,

Fig. 5 is a vertical sectional view taken on the line 5—5 of Fig. 4,

Fig. 6 is an enlarged elevation of the indicating dial for setting the graduating mechanism to obtain predetermined spacing of the type in a line,

Fig. 7 is a perspective view of the rotary or pivoted graduating member,

Fig. 8 is a rear elevational view of a similar type of space graduating mechanism with the parts shown in their respective assembled positions in which the rotary graduating member is provided with a gear segment intermeshing with the rack controlled by the escapement mechanism.

The typewriter structure to which this invention is applied is indicated at 1 and shown in dotted lines which may be any of the standard typewriter constructions now in use, and which has the movable carriage 2 suitably supported thereon and operated by a suitable mechanism in a well known manner. The typewriter constructions now known and used in the art are provided with a suitable standard escapement mechanism indicated at 3 having the star wheel 4 released in a well known manner to permit the step by step operation and movement of the carriage in one direction under the operation of a suitable mechanism well known in the art.

The tabulator bar forming part of the usual carriage structure of the typewriter is illustrated at 5 which is normally mounted in the position shown in the drawing by means of a pair of brackets on the carriage frame. For the purpose of the present invention, these

brackets have been removed and a pair of special brackets indicated at 6 and 7 respectively are employed which are mounted as indicated at 8 on the frame of the carriage 5 for suitably supporting the tabulator bar 5 in its operative position. The tabulator bar is mounted for a limited axial sliding movement on the brackets through the pin and slot connections 9 with the brackets and 10 through the operation of the compensating screw 10 rotatable in the upwardly extending terminal of the bracket 6 as clearly shown in Fig. 2, and threaded in a bore formed in one end of the tabulator bar.

15 This structure provides a compensating means for changing the relation between the graduating mechanism, which will be described, and the carriage.

One end of the tabulator bar 5 which is 20 clearly shown in Figs. 2 and 3, removably mounts the supporting arm 11. This supporting arm is of special shape as clearly illustrated in Figs. 1 to 3 having the curved diagonally extending portion 12 for relative- 25 ly offsetting the end 13 secured to the tabulator bar from the end 14 in order that the last named end will clear the adjacent portions of the typewriter frame and operating mechanism in the movement of the carriage 30 between its operating limits. The end 14 of the supporting arm 11 rotatably supports the bell crank lever 15 rotatably mounted thereon by means of the screw 16 and having one end extending upwardly and provided with 35 a curved diagonally extending portion 17 terminating in the offset end 18 which is provided with a pivoted link connection 19 with the rack bar 20.

The rack bar 20 as illustrated in the drawings, is in the same position as in the standard typewriter structure, being mounted on the rear edge of the carriage frame. In connection with this invention, the usual standard rack bar which normally intermeshes with 40 the gear on the escapement mechanism and controlled by the operation of the star wheel is replaced by a similar rack bar which is indicated by the numeral 20 as above set forth, and is of greater length than the standard 45 rack bar. This bar 20 is provided with a plurality of longitudinally extending slots 21 through which the set screws 22 extend. These set screws are mounted and suitably secured to the rear edge of the carriage frame 50 for mounting the rack bar 20 on the rear edge of the carriage frame for relative sliding movement limited by the length of the slots 21.

The bell crank lever 15 forms the graduating member and has the free end 23 extending in substantially horizontal relation in the rear of the typewriter frame and provided with a guide roller 24 operable in the guideway 25 formed between spaced parallel bars 26 forming a control member 26 and oper-

ating member for the graduating member 15. These parts cooperate to form the space graduating mechanism of the typewriter. The parallel bars are suitably connected by bridge pieces 27 at spaced intervals throughout their length, one of which is positioned in the central portion and formed with a stud 28 extending therefrom threadedly receiving the nut 29 for rotatably mounting the control member on the supporting arm 30 which is 70 removably secured to the rear edge of the main typewriter frame as clearly shown in Figs. 1 and 2.

This control member also mounts a seg- 75 mental rack 31 at one side of the parallel bars 26 as clearly shown in Fig. 4, which intermeshes with the gear 32 mounted on the shaft 33 rotatable in the laterally extending end 34 of bracket 30 and a bearing bracket and setting dial indicated at 35 secured to the front end and at one side of the main typewriter frame as clearly illustrated in Fig. 3. This bearing and indicator dial or setting dial 35 is of annular form as illustrated in Fig. 6 and provided with an extension 36 to permit the mounting of the dial at the left hand side of the keyboard of the typewriter through the use of the same screws that mount the indicator 37 on the frame which controls the setting of the ribbon to obtain the desired 80 color typing. The forward end of the shaft 33 in front of the dial 35 receives the operating knob 38 which carries the setting indicator 39 of ring-shaped formation provided with the indicator wire 40 extending diametrically across the ring 39 and in radial relation with respect to the dial 35.

The outer periphery of the dial is provided with a suitable scale 41 indicating character spacing for a line while the successively inwardly disposed concentric scales 42 are provided to indicate increased and decreased numbers of characters less than a line as compared with the number of characters in the same space at standard spacing which 105 may be desired, in order to obtain the desired spacing of the characters in a line.

From the above description and in comparing the construction as shown in the drawings with a standard typewriter, it should be understood that the escapement mechanism for controlling the movement of the rack bar 20 is in no way changed in this construction from the standard typewriter structure on which this invention is applied, and that the back spacing mechanism together with the carriage speed mechanism and all other associated parts are in no way changed in construction or operation from the standard practice and structure at present in use.

In providing this invention for attachment to standard typewriter structures, it will thus be seen that the operative parts of the typewriter are in no way changed or the construction thereof changed except in the replace-

ment of the rack bar in which a special rack bar structure 20 replaces the standard rack bar but otherwise operates in the same manner in conjunction with the escapement mechanism and star wheel as the standard rack bar. The supporting bracket and mounting for the tabulator bar 5 is changed from the standard practice by the use of special brackets in order to permit the movable mounting 10 of the tabulator bar for compensating between the position of the carriage and the escapement mechanism so that successive lines of typing using varying numbers of characters in a line can have the proper compensation 15 made so that the first character in each line can be alined vertically of the sheets on which they are printed.

With this replacement of only two of the standard parts of a standard typewriter, it 20 will therefore be seen that the several key controlled mechanisms of the standard typewriter are in no way affected in their operation in the usual manner.

The rack bar 20 being directly intermeshed 25 with the pinion on the star wheel shaft of the escapement mechanism has the uniform movement of the rack bar and carriage of the standard typewriter for all conditions of operation so that the rack bar for each step of 30 operation moves the distance the carriage and rack bar is designed to move for standard type spacing. The actuating member or lever 15 pivotally connected by the link 19 to the rack bar 20 as clearly shown in Fig. 2 therefore has a standard movement at the end connected with the link 19 and the rack bar in 35 the normal operation of the typewriter mechanism. By setting the control member 26 so that the guideway 25 is parallel with the rack 40 bar 20, the roller 24 will ride freely back and forth between the parallel bars of the control member 26, the lever 15 will reciprocate in this position of these parts back and forth with the movement of the carriage and the 45 rack bar 20 without rotating on its pivotal connection with the link 19 or with respect to the rack bar 20, or even the control member 26.

In view of the fact that the lever 15 will 50 not rotate with this position of the parts it will be readily understood that the supporting arm 11 for the graduating member 15 will be moved a corresponding distance to that of the rack bar and link 19 and being 55 connected to the carriage will therefore move the carriage to produce standard type spacing throughout the line of type. This will therefore produce standard spacing of the characters in a line as produced by the standard typewriter constructions now in use.

With this understanding of the construction and operation of the parts and with particular reference to Fig. 2, it will be seen that in the travel of the carriage back and forth 60 between its limits of movement with this in-

vention applied, that if the control member 26 is rotated in the bracket 30 so as to assume an inclined position such as illustrated in Fig. 2 with respect to the horizontal plane or in angular relation to the plane of movement 70 of the rack bar, that the movement of the carriage between its limits will cause the roller 24 to ride in the inclined guideway and rotate the control or graduating lever 15 about its pivotal connection with the link 75 19. Thru this rotative movement of the graduating member 15, around the point 16 the carriage through its connection with supporting arm 11 will be moved a greater distance in printing a line of characters 80 and print a fewer number of characters in a line than where the parts are set as above described for the standard spacing of the characters. As a result, greater than standard spacing will occur between the printed 85 characters in a line printed with the parts shown in Fig. 2.

The knob 38 is suitably operated for controlling and setting the control member 26 to obtain the desired type spacing either greater 90 or less than standard type spacing and is set in conjunction with the graduations on the dial 35 to obtain a desired spacing of characters in a line. When the control member 26 is in an opposite inclination to the horizontal plane from that illustrated in Fig. 2, the control member or lever 15 will be rotated in an opposite direction so as to produce a smaller movement of the carriage in comparison with the movement of the rack 100 bar 20 so as to space the type or characters in a line of type printed by the machine closer than standard spacing. In this way a considerably larger number of characters can be printed in a line of predetermined length by 105 this reduced or smaller spacing than is possible with standard spacing.

It will therefore be understood that this invention employs a different principle of operation from that disclosed in the co-pending application and patent above mentioned in employing a rotary graduating member. In order to more clearly illustrate this new graduating mechanism, reference is made to Fig. 8 in which the rack bar 44 is movable 115 under the control of the escapement mechanism for standard stepped movement to produce standard spacing and with which intermeshes the graduating member 45 in the form of an annular disk rotatably supported by the 120 supporting arm 46 suitably mounted on the carriage a portion of which is indicated at 47. This graduating member is provided with an arm 48 projecting from the periphery thereof provided with a roller 49 rotatable 125 on the end and operable in the guideway of the control member 50 as indicated by the numeral 51.

This control member 50 is pivotally mounted on the supporting bracket 52 suitably at- 130

tached to the frame in the same manner as with the construction shown in Figs. 1 and 2 and is adapted to be controlled by the same operating and control mechanism for governing space graduation through the operation of the knob 38. From this illustration in Fig. 8, it will be seen that the rotation of the graduating member 45 is governed by the control member 50 so as to prevent rotation thereof for standard type spacing with the control member in a plane parallel to the rack bar 44 and to increase or decrease spacing of the characters in a line in accordance with the setting of the control member at an angle to the plane of the rack bar for rotating the disc in one direction or the other in the movement of the carriage.

While the rack bar 20 is mounted on the carriage frame, it will have relative movement with respect thereto whenever the space graduating mechanism is set for line spacing of characters greater or less than standard spacing. It will be observed from the drawings that the entire mechanism may be attached to a standard typewriter with the replacement of the rack bar and the brackets 6 and 7 and through securing the support 30 onto the frame by drilling and tapping a pair of holes therein and securing the indicator 35 in place with the same supporting screws as are used for the ribbon indicator. Then the tabulator bar is suitably mounted on the brackets 6 and 7 after being connected to the supporting arm 11 and formed to receive the compensating screw 10. In this way it will be seen that this invention may be readily applied to any typewriter of standard construction in a relatively short space of time, and which upon attachment will sufficiently operate to control space graduation of the type in a line.

With this construction, it will be clear that the rack bar of the escapement mechanism moves in the same direction as the carriage and a greater or less distance than the carriage according to the variation of the line spacing of characters from standard spacing. It is to be further noted that when the control member 26 is set for standard spacing by properly setting the indicator 40 with respect to the registering dial, that the space graduating mechanism is inoperative except as a means for transmitting motion through the pivotal mounting 16 for the graduating member 15 in which the spacing of the carriage is directly controlled by the escapement mechanism.

The set screws 22 may be tightened if desired to rigidly mount the rack bar 20 on the carriage frame when the indicator is set for standard spacing which will effectively render the mechanism inoperative, so that the carriage and the typewriter will operate in the same manner as the standard construction.

With the further reference to Fig. 6, showing the indicating dial and pointer cooperating therewith, it will be noted that the outer edge of the dial is provided with the graduations 41 having cooperation with the indicator wire 40 to indicate character spacing in a line of standard length such as in typewriters built with a ten inch carriage having standard spacing of ten characters to the inch.

It will be understood, however, that this invention is applicable to typewriters having twelve, fourteen, or twenty-four inch characters as well as any other length character made in the construction of typewriters. For this purpose the scale indicated by the numeral 41 on the outer edge of the dial will contain the number of divisions necessary to indicate the length of a line on the typewriter to which it is applied.

With a typewriter having a ten inch carriage, a total of one hundred characters can be typed in a line with standard spacing of ten characters to the inch as above stated. On a typewriter construction of this type, it is usual to only type approximately eighty characters per line or even less according to the margin to be left at the right and left hand sides of the paper. If a line of typing is started on the typewriter scale at the point marked "5" and it is desired to end the line at the point marked "75" on the standard typewriter scale, it will be seen to provide an equal margin at each edge of the sheet for typewriting work, that a copy of the work will first be made with standard spacing, in which the lines will terminate as near the desired point as is convenient, and in the case of each line or a majority of the lines, they will terminate either one, two, three or four characters more or less than the ninety characters to the line.

This will be determined for each line from the standard copy, and then in order to make the spacing equal in each line at each edge of the paper, the graduating mechanism will be set for each line in accordance with the markings on the scale 41, so that it will be set one division to the right or to the left of the point 55 in accordance with whether there were fewer or a larger number of characters in a line, typed with standard spacing. When set in this manner, the line of type by the typewriter set for space graduation through the cooperation of the indicator wire 41 and the dial 35, it will be understood that the lines will all terminate at the same distance from the edge of the paper to provide even starting and termination of the typing in each line.

In this way, the additional or fewer characters are so spaced for each line as to occupy the space between the point "5" and the point "75" on the standard typewriter scale.

That is, the point 55 on the indicator dial indicates the standard spacing of these characters.

acters to a line, while each mark on the scale 41 to the left of the point 55 indicates successively more characters for a line of the same length as the standard line. Each division 5 to the right of point 55 in Figure 6 indicates a successively fewer number of characters for the same length line, such as 79, 78, etc.

Concentrically provided on the face of the disk with respect to the scale 41 and inwardly thereof, are a plurality of circumferential markings 56, 57, 58 and 59 respectively, which as shown in Fig. 6, have the numerals "6", "4", "3", "2", respectively, at the ends thereof for indicating linear measure in inches. If 10 it is desired to have four characters more than the number obtained by standard spacing in a two inch space, the indicator wire 41 will be moved so that it will be set opposite the fourth dot to the left of the point 55 on the 15 circle indicated by the numeral 59. Should it be desired to have one or more characters less than the standard number in a two inch space, then the indicator wire 41 is set in line with the desired dot according to the number 20 of characters less than the standard number in a two inch space to the right of the 25 point 55 on the circle 59.

Likewise, should it be desired to have four additional characters in a six inch space, the 30 indicator wire 41 would be set to register with the dot 61 on the concentric circle 56 and if four characters less than the standard number in a six inch space were desired, then the indicator would be set to the point 60 on the 35 circle 56.

In this way it will be seen that through the operation of the indicator, the spacing of the typewriter may be changed to obtain any desired number of characters in a line or in 40 any suitable space by the operation of the pointer carrying the wire 40 at the desired point or scale graduation formed on the dial 35.

A construction of this type is especially desirable for form letter work or any form of 45 tabulating work in order that the typing space may be limited so that within the desired limits the typing will begin and end in the same vertical plane on the paper.

While the compensating mechanism above set forth may be used in connection with a construction of this type, it has been found that the carriage for any space graduation has a center point on the standard scale for vertically aligning one or more characters in adjacent lines, and in the construction shown in the drawings, the parts are centered so that the carriage will always center on the division "45" on the standard typewriter scale regardless of the setting of the space graduating mechanism by the operation of the knob 38 and the setting of the pointer on the dial. It has been found from practical experience that this centering can be obtained at any desired point on the standard scale of the type-

writer and for general types of work, will be fixed so that it will center at the zero point or adjacent thereto.

In view of this operation of these parts with this centered relation, it should be readily appreciated that the support 30 for the control member 26 can be made adjustable in a plane parallel with the movement of the carriage so as to set the center point at any desired point on the standard typewriter scale 75 for desired purposes.

It is to be further understood that if desired the scale can be placed on a strip of metal so that instead of cooperating with a rotary pointer, the strip of metal will provide 80 a linear scale with a slide member movable therein and having suitable mechanism for connecting it with the control member to insure the setting of the control member in accordance with the setting of the slide member 85 on the linear scale.

Having thus described our invention, what we claim as new is:—

1. In a line spacing graduating attachment for typewriters comprising in combination, a typewriter frame, having its carriage operatively mounted thereon and an escapement mechanism operable to control the movement of the carriage, movable means mounted on the carriage forming a single 95 direct connection between the same and the escapement mechanism for transmitting motion of said mechanism to the carriage, a control member pivotally mounted on the frame and connected with the movable means, 100 adapted to vary the ratio of movement between the carriage and escapement mechanism either to increase or decrease the same, adjustable means to vary the position of the control member and a position indicator for 105 said control member operable through the adjustable means.

2. In a line spacing graduating attachment for typewriters comprising in combination, a typewriter frame having a carriage operatively mounted thereon and an escapement mechanism operable to control the movement of said carriage, an arm rigidly attached at one end to the carriage, a bellcrank lever fulcrumed at the opposite end thereof, a pivoted 115 link connecting one end of the lever to the escapement mechanism, a control member forming a sliding connection with the opposite end of the lever, means for adjusting said control member whereby to vary the 120 ratio of movement between the carriage and escapement mechanism to increase or decrease the same and a position indicator for said control member operable through the control member adjusting means.

3. In a line spacing graduating attachment for typewriters comprising in combination, a typewriter frame having a carriage operatively mounted thereon and an escapement mechanism operable to control the 130

movement of said carriage, an arm rigidly attached at one end of the carriage, a bell-crank lever fulcrumed at the opposite end thereof, a pivoted link connecting one end 5 of the lever to the escapement mechanism, a control member pivotally mounted intermediate its ends to the frame forming a sliding connection with the opposite end of the lever,

an adjusting shaft, a rack and gear connection between the same and the control member and a position indicator for said control member operable through the shaft. 10

In testimony whereof we affix our signatures.

KENNETH C. O'BRYAN.
JAMES W. O'BRYAN.
